[57] CLAIM

The ornamental design for an ice cube tray having a slidable cover, as shown and described.

DESCRIPTION

FIG. 1 is a perspective top view of the ice cube tray having a slidable cover in a fully closed position;

FIG. 2 is a perspective bottom view of the tray shown in FIG. 1;

FIG. 3 is a top view of the tray shown in FIG. 1;

FIG. 4 is a side view of the tray shown in FIG. 1, both side views being the same;

FIG. 5 is an end view of an end of the tray shown in FIG. 1, end views being the same;

FIG. 6 is a cross-sectional side view of the tray taken along the axis 6—6 in FIG. 3;

FIG. 7 is a cross-sectional side view of the tray taken along the axis 7—7 in FIG. 3; and,

FIG. 8 is a cross-sectional end view of the tray taken along the axis 8—8 in FIG. 3.

The surface(s) or portion(s) of the article not shown in the drawing or described in the specification form(s) no part of the claimed design.
